LIFTING DEVICE FOR COILED MATERIAL

Richard E. Compson, Roseville, Mich.

Application June 30, 1954, Serial No. 440,423

4 Claims. (Cl. 294—97)

This invention relates to a device for handling stacked coiled material.

It is an object of this invention to provide a device of the type described which is simple in its construction and which is designed to be operated readily by a remotely located operator.

In the drawings:

Fig. 1 is a side elevational view of the lifting device of this invention, the device being shown in a collapsed condition inserted within a stack of coiled material.

Fig. 2 is an end view of the device in the position shown in Fig. 1.

Fig. 3 is a side elevational view of the device in the expanded condition wherein it engages with the bottom of the stack of coiled material.

Fig. 4 is a fragmentary detailed sectional view of the latch arrangement for holding the arms of the device in the collapsed condition.

The device of this invention generally includes a pair of levers 10 and 12 each of which is in the form of a bell crank having a relatively short arm 14 and a relatively longer arm 16. The arms 14 and 16 are formed integrally and are connected by a web portion 18. Members 10 and 12 are pivotally connected together as by a bolt 20 and a nut 22 which passes through registering openings in the web portions 18. Members 10 and 12 are preferably fashioned as heavy steel stampings. They may, if desired, be formed as steel castings or forgings, however. At their lower ends, the arms 16 are provided with lateral extensions 24 on which support plates 26 are welded or otherwise secured. The members 10 and 12 are reversely positioned so that the arms 14 and the extensions 24 normally project in generally opposite directions.

The outer ends of arms 14 are provided with apertures 28 therein for connecting to the ends of these arms cables 30, which are connected at their opposite ends to a lifting device such as a crane or the like (not shown). An operating lever 32 is pivotally supported on members 10 and 12 as by the bolt and nut 20, 22 which pivotally connects the members 10 and 12. Lever 32 is also fashioned as a bell crank and has arms 34 and 36 projecting from the pivotal connection 20, 22. Arm 34 is provided with an aperture 38 at the free end thereof to which is attached a control cable 40. Cable 40 extends through suitable guides on the crane or other lifting mechanism to the control platform so that it can be actuated by the operator of the mechanism. The other arm 36 of lever 32 has a roller 41 mounted at the free end thereof. Roller 41 is arranged to rollably engage the substantially straight upper edge 43 of arm 14 on lever 10.

There is also provided a latch mechanism for locking the members 10 and 12 in the collapsed position shown in Fig. 1. This latch mechanism comprises a bushing 42 which is secured as by cap screws 44 to the exposed face of member 10 at a point spaced above the pivot bolt 20. Bushing 42 has a bore 46 therein which, when the levers 10 and 12 are in the collapsed condition shown

in Fig. 1, is aligned with registering openings 48 and 50 in members 10 and 12 respectively. Within the bore 46 and the aligned aperture 48 in member 10, there is slidably arranged a locking pin 51 having a head 52 and a reduced shank portion 54. A spring 56 acting between head 52 and a shoulder 58 on bushing 42 normally urges the head 52 in a direction towards member 12 so that when the openings 48 and 50 are aligned, head 52 is automatically projected by spring 56 into opening 50. A pin 60 extending transversely through the free outer end of the reduced shank portion 54 provides a convenient means for actuating the locking pin 51.

In use, when it is desired to lift a stack of coiled material such as shown at 62, which for the purposes of illustration is shown supported on a pair of supporting blocks 64, the arms 16 are pivoted towards each other to the position shown in Fig. 1; and the locking pin 51 is in the latching position. In this condition, the device may be lowered by the crane operator into the central opening 66 of the stacked material by lowering or extending the cables 30. When the device has been lowered to a position wherein the support plates 26 are disposed below the lower edges of the stacks 62, a man on the floor where the material 62 is stacked retracts locking pin 51 so that the head 52 is withdrawn from within opening 50. At this time, the cable 40 is slack and the members 10 and 12 by reason of the lifting cables 30 are pivoted to the position shown in Fig. 3 wherein the extensions 24 and the support plates 26 underlie the bottom faces of the stack 62. The crane operator then pulls up on the cables 30 and the stacked material 62 is thus raised.

After the stacked material 62 is swung by means of this device to the desired location, cables 30 are lowered to position the stacked material 62 on another pair of supports similar to supports 64. After the stack 62 is firmly supported on the supports, the cables 30 are further lowered so that the plates 26 are moved downwardly out of engagement with the bottom face of the stack. In this condition, the arms 16 will tend to maintain their separated condition shown in Fig. 3. In order to retract the device from within the stacked coiled material, it is necessary to pivot the members 10 and 12 to a position wherein the arms 16 generally overlie one another as shown in Fig. 1. This can be readily accomplished by the crane operator by simply pulling up on cable 40. When cable 40 is pulled upwardly, the operating lever 32 is rotated in a clockwise direction as viewed in Figs. 1 and 3, and the roller 41 at the free end of arm 36 presses downwardly on the upper edge 43 of arm 14 on member 10 and rotates member 10 in a clockwise direction about the bolt 20. This causes the pivotal connection 20, 22 to shift upwardly, and both arms 16 pivot toward one another to the position shown in Fig. 1. When the arms 16 assume the position shown in Fig. 1, the plates 26 forming stops as shown, openings 48 and 50 in members 10 and 12 respectively will be aligned; and spring 56 thereby causes the head 52 of locking pin 51 to be projected into the opening 50 thereby locking the members 10 and 12 in the position shown in Fig. 1. The crane operator can then lift the device from within the stack 62; and after centering it over another stack of coiled material, lower it into the position generally shown in Fig. 1.

Thus it will be seen that I have provided a device for lifting coiled material which is of very simple construction. The device, however, is very rigid; and the shape of the members 10 and 12 together with the provision of the operating lever 32 and the latch mechanism shown specifically in Fig. 4 enables the device to be used very conveniently and in a very simple manner for lifting coiled material.

I claim:

1. A device for lifting stacked coiled material of annular form comprising a pair of bell crank levers each having a pair of angularly related arms, said levers being reversely positioned and pivotally connected together adjacent the intersection of said arms whereby when one set of corresponding arms are juxtaposed, the other set of corresponding arms project in generally opposite directions, one pair of said corresponding arms being provided with lateral extensions at the free ends thereof and the other pair of corresponding arms having means at the free ends thereof for securing lifting members thereto, said levers being normally positioned with said arms provided with said lateral extensions in generally juxtaposed relation and an operating lever pivotally supported intermediate its ends at the pivotal connection between said first mentioned levers and having a roller at one of its free ends and means at its other free end for pivotally actuating the operating lever, one of said first mentioned levers having an edge portion on which said roller travels when said operating lever is pivotally actuated so as to pivotally actuate said one of said first mentioned levers when the operating lever is pivotally actuated.

2. A device for lifting stacked coiled material of annular form comprising a pair of bell crank levers each having generally perpendicular related arms, one of said arms being longer than the other, said levers being pivotally connected together adjacent the intersection between said arms and being reversely positioned relative

4
to each other such that when the longer arms of the two levers are in generally overlying position, the shorter arms of said levers project in generally opposite directions, the free ends of said shorter arms having lifting members connected thereto and the free ends of said longer arms having laterally extending foot portions thereon and including an operating lever on said device, said operating lever being pivoted on said device at said pivotal connection between said levers and having one free end portion engageable with one of said levers and another free end portion to which is attached an actuating member, said actuating member comprising a control cable.

3. The combination called for in claim 2 wherein said one free end of the operating lever is provided with a roller, said one of said first mentioned levers having an edge portion engaged by said roller.

4. The combination called for in claim 3 wherein said edge portion is fashioned on the shorter arm of the last mentioned lever.
